1 Claim. (Cl. 230—141)

This invention relates to improved Root's type high vacuum pumps, and is a division of my co-pending application Serial No. 490,316, filed February 24, 1955, now abandoned.

Root's type pumps (also known as Connersville blowers) have been in use for many years, and are described in technical literature such as "Industrial Chemistry," by E. R. Riegel, Reinhold Publishing Corporation, pp. 696-7.

In a typical Root's pump, a pair of parallel and laterally spaced shafts are journaled in a casing which has an inlet and an outlet. Separate impellers mounted on each shaft mesh as the shafts are rotated and sweep fluid from the inlet to the outlet. Such pumps have been used in the past principally for moving relatively large volumes of liquid or gas under atmospheric or higher pressures and at moderate rotational speeds, say, several hundred revolutions per minute.

In the past, it has been considered good practice to provide the Root's type pump impellers with roughened surfaces to reduce the back flow of gas, the thought being that the roughness reduced the clearances between the moving parts and the pump and provided increased impedance to back flow of gas. However, I have discovered that in operating Root's type pumps in the vacuum range, say less than 50 mm. Hg, roughness of the impeller surface and the interior casing surface not only fails to improve pumping efficiency, but actually impairs it.

According to this invention, I provide a Root's type pump for operation in the pressure range of less than 50 mm. Hg in which the surfaces of the impellers are made microscopically smooth, and of an impervious material which does not absorb or adsorb significant quantities of gas molecules. Preferably, the interior of the casing is also made gas impervious and microscopically smooth. The discovery that a Root's pump of improved efficiency is obtained by making the impellers and casing interior as smooth as possible is an unexpected result in view of the previous practice of the industry either to leave the surfaces of the impellers untreated or else deliberately increase the roughness of the surfaces of the impellers.

Even a small degree of roughness in the surfaces of the impellers or pump casing provides minute dead spaces or pockets in which traces of gas can settle and not be readily pumped. As long as Root's pumps are operated at relatively high pressures, say, atmospheric pressure, this phenomenon either does not occur or is not significant. However, in the low pressure ranges, particularly less than a few mm. Hg, even small quantities of gas trapped in the surface pockets seriously impair the efficiency of the pump. For example, as a portion of an impeller with a rough surface moves through a high pressure zone to force gas toward the pump outlet, countless pockets become full of relatively high pressure gas. As the piston moves into the low pressure zone of the pump, gas trapped in the pockets can escape into the low pres-

2

sure zone and prevent the pump from obtaining the desired low pressures.

In using the Root's type pumps for the higher pressure ranges, say, atmospheric pressure and higher, it has always been general practice to make clearances as small as possible to improve pumping efficiency. However, in using the Root's type pump as a vacuum pump, particularly below about 20 mm. Hg, the clearances between the moving parts of the pump can be considerably increased with little harm to the pumping efficiency because of the relatively large mean free path of the gas molecules. For example, clearances between moving parts can be .1 mm. and larger. This permits the pumps to be operated at exceptionally high rotational speeds, say 2,000 to 3,000 revolutions per minute, which further improves their efficiency as high vacuum pumps.

Thus, by providing a Root's type pump for operation in the vacuum range with sufficiently large clearances for high speed operation and a highly polished surface for the impellers, a pump of improved efficiency can be obtained.

The advantages of a Root's type pump having relatively large clearances and highly polished interior surfaces can be further improved by making the impellers of light construction, which aids in the high speed operation of the pump. Light construction can be achieved, for instance, by making the impellers hollow instead of solid, as has been the past practice. The impellers can also be made of very light sheet metal and made up of individual sections which are assembled on the pump shafts to form an integral unit.

These and other aspects of the invention will be more fully understood from the following detailed description taken in conjunction with the accompanying drawing

35 in which:

Fig. 1 is a schematic sectional elevation of a Root's type pump having hollow impellers in accordance with this invention; and

Fig. 2 is a schematic perspective view, partially broken 40 away, showing an impeller made of segments in accordance with another form of this invention.

Referring to Fig. 1, a Root's type pump includes a pump casing 10 in which a pair of Root's type impellers 11 are each mounted on rotatable shafts 12. A pump inlet 13 is on one side of the casing, and an outlet 14 is on the other side of the casing. The outlet is adapted to be connected to a suitable fore-vacuum pump (not shown), for example, a conventional mechanical oil sealed rotary pump, which reduces the back pressure on the outlet of the Root's pump to less than 50 mm. Hg. 50 Each impeller has a pair of longitudinal bores 15 to reduce their weight and improve the operating characteristics of the pump at high rotational speeds.

Referring to Fig. 2, impeller 20 is mounted on a shaft 21. The impeller includes an outer shell 22 which may be of thin sheet metal or of a rigid inorganic plastic, for example. In either case the surface of the impeller is microscopically smooth and has a highly polished appearance. The interior of the shell includes a series of longitudinally spaced ribs 23 having their outer surfaces shaped to conform with the cross section of the impeller. Each rib has a pair of openings 24 on opposite sides of the shaft to reduce the total weight of the impeller, and each rib is spaced from adjacent ribs by spacer sleeves 25 disposed around the shaft. The ends of the impeller are closed by solid stiffener plates 26 which also have their edges shaped to match the cross section of the impeller surface. As viewed in Fig. 2, only one stiffener plate is visible. A small opening 27 in one of the stiffener plates permits the gas pressure in the impeller interior to become substantially equal to that of the working pressure in the pump. The impeller shown in Fig.

2 is of extremely light construction and well adapted for high speed operation.

In accordance with this invention, the impellers of either the type shown in Fig. 1 or the type shown in Fig. 2 are provided with microscopically smooth surfaces. The smooth surfaces are provided by any of several well-known techniques. For example, the surfaces can be made extremely smooth by very fine polishing or by the coating of the impeller surfaces with layers of material which have already been polished. For example, sheets of hard organic synthetic plastic with extremely smooth or polished surfaces can be bonded to the impeller surfaces.

Smooth surfaces can also be provided by applying to the impeller surfaces suitable coating materials. For example, smooth varnish, enamel, metallic, or oxide coatings may be applied by dipping, spraying or by suitable vacuum coating operations which are well-known to those skilled in the coating art. For example, a highly polished chromium plating provides a corrosion resistant surface, and a surface which improves pumping efficiency.

Smooth layers can also be applied by cathode spraying or evaporation in vacuum, or by electrolytic or electrochemical processes. Any of the well-known methods for improving the smoothness of surfaces can be utilized in this connection to give the surfaces a smooth vitreous-like finish.

The interior of the pump casing is also provided with a smooth surface by any of the above described methods.

Thus, this invention provides an improved Root's type pump with lightweight impellers for high vacuum operation in which the pump is adapted to operate at high rotational speeds and has highly polished or smooth interior surfaces to improve pumping efficiency in the vacuum range below about 50 mm. Hg.

I claim:

A Root's type vacuum pump for operation at very high mechanical speeds above 2000 r.p.m. and at absolute pressures below 50 mm. Hg comprising a casing

having an inlet and an outlet, a pair of shafts journaled in the casing for rotation, and a pair of rotatable impellers mounted on the respective shafts in the casing, the impellers being adapted to intermesh without actually touching in the central region of the casing to drive gas from the casing inlet toward the outlet, the surfaces of the impellers and adjoining interior surfaces of the casing having a microscopically smooth finish with a substantial clearance between the intermeshing surfaces of the two impellers and between the surfaces of the impellers and the interior of the casing, whereby no sliding friction is generated by rotation of the impellers, each of the impellers including a plurality of longitudinally spaced transverse reinforcing ribs secured to the associated shaft, the ribs having an outline conforming to the desired cross-sectional shape of the impeller, the ribs having large openings therethrough to decrease their weight, a pair of solid end plates secured to the associated shaft having the same outline shape as the ribs, and a skin of thin flexible material formed around and conforming to the outline shape of the ribs and end plates, the skin being secured along the edges thereof to the end plates to form a light hollow impeller body.
